United States Patent Office

Des. 215,293
Patented Sept. 23, 1969

215,293

ELECTRONIC TEACHING UNIT

Yo Sakakibara, Shibuya, P.O. Box 140,
Tokyo 150-91, Japan

Filed July 25, 1968, Ser. No. 12,903

Term of patent 14 years

Int. Cl. D19-08; D14-01

U.S. Cl. D25-1

FIGURE 1

FIGURE 2

FIGURE 3

FIGURE 1 is a front perspective view of an electronic teaching unit showing my new design;

FIGURE 2 is a perspective view illustrating the rear and top of said unit;

FIGURE 3 is a left side elevation view of said unit; and

FIGURE 4 is a right side elevation view of said unit.

I claim:

The ornamental design for an electronic teaching unit, as shown.
